US00D802294S

(12) **United States Design Patent** (10) **Patent No.:** **US D802,294 S**
(45) **Date of Patent:** **** Nov. 14, 2017**

(54) **HYDRATION SLEEVE**

- (71) Applicant: **DGM Creations LLC**, West Palm Beach, FL (US)
- (72) Inventors: **Kyle Sola**, Brooklyn, NY (US); **Marcel Geser**, Zurich (CH); **Franziska Rieder**, Zurich (CH)
- (73) Assignee: **DGM Creations LLC**, West Palm Beach, FL (US)

(**) Term: **15 Years**

(21) Appl. No.: **29/575,806**

(22) Filed: **Aug. 29, 2016**

(51) LOC (10) Cl. **03-01**

(52) U.S. Cl.

USPC **D3/202**; D3/215; D7/515

(58) **Field of Classification Search**

USPC D7/507, 510, 509, 300.1, 300, 397, 514, D7/515; D3/202, 215; 222/175, 224/148.6, 148.2, 148.3

CPC A45F 3/20; A45F 2005/008; A45F 5/00; A45F 3/16

See application file for complete search history.

(57) **CLAIM**

The ornamental design for hydration sleeve, as shown and described.

DESCRIPTION

FIG. 1 is a perspective view of a hydration sleeve showing our new design;

FIG. 2 is a front view of a hydration sleeve shown in FIG. 1;

FIG. 3 is a rear view of the hydration sleeve shown in FIG. 1;

FIG. 4 is a right side view of the hydration sleeve shown in FIG. 1;

FIG. 5 is a left side view of the hydration sleeve shown in FIG. 1;

FIG. 6 is a top plan view of the hydration sleeve shown in FIG. 1; and,

FIG. 7 is a bottom plan view of the hydration sleeve shown in FIG. 1.

The broken lines in the drawing depict environmental subject matter only and form no part of the claimed design.

1 Claim, 7 Drawing Sheets
